PALLETIZER ROLLER

E. Donald Glassner, Ellisville, and Harold W. Becker, St. Louis County, Mo., assignors to Urethane Roller Specialists, Inc.

Filed May 17, 1974, Ser. No. 470,735

Term of patent 14 years

Int. Cl. D12—05

U.S. Cl. D55—1 C

FIG. 1.

FIG. 2.

FIG. 3.

FIG. 4.

FIG. 1 is a view in perspective of palletizer roller for beverage case palletizing machine showing our new design;

FIG. 2 is an enlarged side elevational view about the line 2—2 of FIG. 1, partly broken away;

FIG. 3 is a sectional view taken along the line 3—3 of FIG. 2; and

FIG. 4 is a view in side elevation, partly broken away, of palletizer roller of this invention utilizing a modified design.

We claim:

The ornamental design for palletizer roller, as shown and described.
